STARTER LEVER FOR POWER LAWN MOWERS

Robert L. Konle, Waukesha County, Wis., assignor to Food Machinery and Chemical Corporation, San Jose,
Calif., a corporation of Delaware

Application August 28, 1957, Serial No. 47,536

Term of patent 14 years

(Cl. D40—1)

Fig. 1 is a perspective view of a starter lever for power lawn mowers embodying my new design, the mower shown in broken lines being for illustrative purposes only;

Fig. 2 is a top plan view thereof; and

Fig. 3 is an elevational view showing the side opposite the side shown in Fig. 1.

I claim:

The ornamental design for a starter lever for power lawn mowers, as shown and described.
